UNITED STATES PATENT OFFICE

2,083,509

CIRCUIT BREAKER

Lambert Schmidt, Leeds, N. Y.

Application June 18, 1935, Serial No. 27,176

15 Claims. (Cl. 200—116)

This invention relates to circuit breakers and has for its object to provide certain improvements in circuit breakers of the type for which I now have pending an application for Letters 5 Patent of the United States, Serial No. 702,153, dated December 13, 1933. By means of these improvements in the case of a short circuit or a flow of electricity greater than that normally intended, the circuit cannot be permanently closed. 10 Such closing of the circuit brings about a short circuit on the main circuit or burns out the parts of the circuit breaker.

An object of this invention, accordingly, is to provide, in circuit breakers of the above type, 15 mechanism by means of which the breaker contacts may be maintained in an open position regardless of whether manual pressure is exerted upon the closing mechanism or not.

A further object of the invention is to provide, 20 in combination with mechanism of the above character, a free tripping mechanism which serves as a connection between the manual operating mechanism and the movable breaker element, such mechanism rendering the connection between these elements inoperative to maintain the breaker contacts in closed position by continued manual pressure upon the starting mechanism.

A further object is to provide free tripping 30 mechanism of the above character, the structure of which is independent of the structure of the circuit breaker, thus enabling the breaker elements to be of such construction that the breaker structure may be of minimum size.

35 A further object of the invention is to provide indicating means by which a user may immediately detect whether or not an overload or short circuit is present. This indicating means warns against operating the push-button of the circuit breaker and therefore enables the user to see whether or not the device is out of working order.

40 For this purpose an important feature of the invention lies in the freedom of the operating rod of the circuit breaker under spring action, so that the circuit will not be permanently closed. This is accomplished by giving the rod an unimpeded movement which will avoid the rod being held back and will enable it to be free to move without making permanent contact; in other 45 words, a free tripping device is provided.

The invention, consists in further providing 50 indicating means operative in such cases where the rod itself does not close the circuit and where the circuit is under current flow above the pre-determined normal amount.

The invention is shown as embodied in the structure depicted in the drawings, and will be hereinafter more fully described in the light of this embodiment, and finally set forth in the subjoined claims. 5

In the accompanying drawings:—

Figure 1 is a vertical section taken through a circuit breaker showing my improvements embodied therein;

Figure 2 is a plan view or section taken on 10 line 2—2 of Fig. 1;

Figure 3 is a section similar to that of Fig. 1, but showing only certain parts of the device shown in Fig. 1 and showing them in different operative positions; 15

Figure 4 is a perspective view of the guide springs or rod-holding device;

Figure 5 is a partial side view of the piston sleeve to operate the spring fingers shown in Fig. 4; 20

Figure 6 is a side view of the rod which enters the sleeve of Figure 5 and slides in respect thereto, and is either impeded by the spring fingers shown in Figure 4 or is left free to pass therethrough by the opening of the spring fingers by 25 the sleeve shown in Figure 5;

Figure 7 is a section of the parts shown in Figure 3 in different positions, and embodying a further improvement in the form of an indicating device; 30

Figure 8 is a side view of an attachment plug of a different type than that shown in Figure 1, Figure 8 showing a thrust-in type of attachment plug which is also an embodiment of the invention; 35

Figure 9 is a section view of another embodiment of the signalling device;

Figure 10 is a plan view taken on line 10—10 of Figure 9;

Figure 11 is a sectional view of another embodiment; 40

Figure 12 is a similar view taken at right angles to that of Figure 11;

Figure 13 is a sectional view of another embodiment of the thermostatic control which acts 45 to hold the switch rod and also acts as a contact device;

Figure 14 is a plan view taken on line 14—14 of Figure 11;

Figure 15 is a plan view taken on line 15—15 of Figure 11; and 50

Figure 16 is a plan view of a contact plate.

Similar characters of reference indicate corresponding parts throughout the various views.

Referring now to the drawings, and more par-

ticularly to Figure 1, the plug casing 10 has a threaded portion 11 and a contact piece 12, as is well known. Disposed within the plug casing 10 is a socket member 13 to which is pivotally attached a spring plate 14 having an opening 15, the edge of which opening is adapted to be engaged by the plug 16 on the rod 17. When the plug 16 engages the edge of the opening 15, the rod 17 is held in downward locked position. This locking device forms the basis of my above-mentioned pending application.

A thermostatic member 18 of horse-shoe form is supported by the studs 18a, and this member is so arranged that when current in excess of that which can be considered normal, passes through the member 18 the free end of the latter descends and the plate 14 is actuated in a downward direction. When this plate 14 is moved downwardly the edge of the opening 15 is dis-engaged from the plug 16 and the latter with the rod 17 is free to move upwardly under the action of the spring 19 which spring is seated in the bottom of the socket portion and acts against the plug 16. The rod 17 has a contact member adapted to engage three or more spring-like prongs indicated by 21. When the contact member 20 which is of plunger form, is forced into spring-like members 21 and engaged thereby and held in position therein, the electric current passes through the contact members, that is, the electric circuit is closed when the member 20 engages the members 21. The member 20 is held in position within the spring-like contact members 21 and the rod 17 has its plug 16 locked by the spring plate 14, as above described. Upon the operation of the horse-shoe member 18 by an excess current, the spring plate unlocks itself by reason of the spring member 19 and the rod 17 is forced upwardly whereupon the members 20 and 21 are disengaged and the circuit is broken.

This unlocking action can also be accomplished by means of an external push-button 22, having a rod 23 which extends through casing 10 and through the recessed end 18b of the thermostatic member 18 to the spring-plate 14. Downward pressure on button 22 presses the plate 14 downwardly and unlocks rod 17. Thus rod 17 under its spring action, as above described, may ascend and break the circuit.

It has been found that in cases where the thermostatic couple operates to release the rod, the rod will again be pressed downwardly and, when the parts are under an overload current, they burn out or short circuit results. If a user repeatedly presses down on the push-button, as 25, short circuits in the entire system may result. To overcome this, my improvement which forms the basis of the present application consists in the following mechanism:

Spring fingers 26 provided with jaws 27, such as shown in Fig. 4, are arranged within the push-button 25. These spring fingers extend upwardly from a base portion 28, which base portion seats in a suitable recess 29 at the lowermost portion 65 of the push-button 25. A sleeve 30 has a rounded end portion 31 (shown also in Fig. 5) and a plate 33. In the embodiment, the sleeve 30 is supported upon or is made integral with the plate 33 which is held to the casing 10 by screws 34, a spring 35 of spiral shape being interposed between the plate 33 and the bottom of the push-button 25. This is clearly shown in Fig. 1, where the spring is shown in extended position, and in Fig. 3 where the spring is shown in compressed position.

The operation of the embodiment described is explained as follows: When an excess of current acts upon the thermostatic couple 18, this member is moved downwardly, whereby the plate 14 is unlocked from plug 16, and rod 17 is free to move upwardly under the action of its spring 19. If the push-button is now pressed down, the jaws 27 of the spring fingers 26, will engage the flat end 17a of the rod 17 and move it downwardly. This downward movement of the rod 17 continues until the push-button arrives at a position wherein the bent portions 32 of the spring fingers 26 meet the rounded portion 31 of the sleeve 30, through which the rod is free to slide. Upon further downward pressure applied to the push-button 25, the rounded portion 31 opens the jaws 27, and the rod 17 is free to pass therethrough. The spring 19 then forces the rod 17 upwardly with great rapidity. In the meantime, the contact member 20 has made momentary contact with the contact member 21, but this is only instantaneous. The user pushing the push-button, can do so repeatedly and each time the rod 17 will jump upwardly with great rapidity, and no harm can result therefrom. This result is predicated upon the fact that the overload acts upon the thermostatic couple 18 which in turn presses the spring rod downwardly to prevent the spring rod from locking the rod 17. In consequence of the downward pressure of the push-button 25, the rod is first pushed down by the jaws 27 and then passes through the jaws 27, as shown in Fig. 3, and while this causes the members 20 and 21 to contact, there is nothing to hold the rod in its downward position or to maintain it in its downward position, and therefore under the action of the spring 19, it immediately and instantaneously jumps upwardly until the plug 16 reaches the plate 33. While contact is made between the contact members, it is insufficient to cause a destructive current to pass through the members 20 and 21. By virtue of this arrangement of parts, the push-button 25 can be pushed down repeatedly but the rod 17 will always jump through and refrain from making a permanent electric circuit, and therefore all danger of short circuiting to the system is obviated.

With the embodiment shown in Fig. 1, it may possibly be that the user will continue to press down and cause rod 17 to be moved downwardly 50 and instantaneously jump back and at the same time wonder why no current passes through to light the lamp or the like, and in order to prevent such repeated action, an indicating device is provided. An embodiment thereof is shown 55 in Fig. 7, in which a plate 40 has two upwardly extending rods 41 which pass through openings 42 in the top of the casing 10, and upon these rods 41 enlarged portions or buttons 43 of a suitable color, such as results from a bright 60 bakelite, preferably red, are arranged. The plate 40 has a central opening 44 somewhat larger than the diameter of the rod 17, so as to permit the rod 17 to freely move through said opening 44. A spring 45 is interposed between the plate 40 and the plate 33, which in this embodiment, has a shoulder portion 46 in order to act as a seat for one end of the spring 45. In the normal closed position of the device the plate 40 is in the position shown in Fig. 7, 70 that is, with the buttons 43 hidden in their sockets 47. The plate 40 is disposed immediately above the plug 16 on the rod 17, and on the upward movement of the rod 17 and its plug 16, the plate 40 is carried along and thereby 75

the buttons 43 are exposed exteriorly to the casing, whereby they are visible. When visible, the user will see the danger indication and will refrain from pressing down the button 25. Thus when the plug 16 of the rod 17 presses upwardly against the plate 33, through the plate 40, the danger signal will be visible. When, however, the rod 17 makes a permanent contact through the members 20 and 21, then the spring 45, 5 presses the plate 40 downwardly, and this causes the signals 43 to disappear in their sockets.

When, however, the circuit is in a normal condition and the plate 18 is in its open position and it is desired to close the circuit, then 15 the push-button 25 is pressed downwardly and the jaws 27 engage the flat end 17a of the rod 17, whereby on the downward pressure of the push-button 25 with the jaws 27 in contact with the flat end 17a of the rod 17, the rod 17 is 20 pressed downwardly and the spring plate 14 locks the plug 16 in position, whereby the contact members 20 and 21 are made permanent and the circuit is closed.

From the foregoing, it will be seen that with 25 the arrangement of the sleeve 30 upon the rod 17, which sleeve has a rounded portion 31 to move the jaws 27 outwardly and open the same, the rod 17 may freely move up and down without permanent engagement of the contact 30 members 20 and 21. On the other hand, when the rod 17 encounters the jaws 27, the downward pressure of the push-button 25 forces the contact members 20 and 21 in permanent engagement with each other under the locked position of rod 17. The current path through the foregoing mechanism flows from the shell 11 to the lower post 18a in Figure 2 which is seen as being insulated from the plate 13. From this post the current flows through element 18, 35 plate 13, rod 17 and contact terminals 20 and 21 to the central contact 12.

It is also to be noted that the arrangement of the plate with the indicating buttons 43 provides a very simple and assured means of indicating a danger sign to the user of the device, in case either excess current moves the member 18 downwardly against the plate 14, or the rod 23 is pressed normally downwardly against the plate 14.

50 The various embodiments which have been described have been shown in connection with Figure 1 as applied to a screw-threaded plug, but it is clear that instead of a screw-threaded portion, the thrust-in prongs may be used in place 55 thereof, the mechanism described being as well applicable to the form shown in Figure 8, as to the form shown in Figure 1.

In Figure 8, the casing 50 has a button 51 similar to push-button 25, with circuit conductors 52 and 53, and with metallic contact prongs 54 and 55.

A form of signalling device was described in connection with Figure 7. Another embodiment of the same is shown in Figure 9. A spring 65 plate 80 is secured by the screw 81 to the casing 10. This spring plate 80 has a bore 82, through which the rod 17 freely passes. The free end of the plate 80 has an opening 83, to enable a stud 84 to pass through the larger part of the 70 opening 83 and be moved along the elongated part of the spring. The stud 84 has a recessed portion 85 to enable the plate to engage the stud as shown in Figure 9. When plug 16 of the rod 17 presses against the plate 80 the stud 84 will 75 be moved exteriorly to the casing 10 and be

visible, either by being flush with the casing or extending slightly above it. The stud 84 can be given a suitable color and, when visible, acts to signal that contact is broken so as to tell the user not to keep on pushing the push button 25. The manual release 71 is shown, but needs no further description in connection with this embodiment.

Another embodiment of the thermostatic control is shown in Figures 11 to 16. The control now serves a triple function, first it acts as a thermostatic control, secondly, it acts to hold the switch rod, and thirdly, it acts as a contact.

The control 90 is placed on the bottom of the casing. It has enlarged spring plate portions 91a fitted to frictionally and huggingly engage the lower enlarged end 91 of the switch rod 17 when inserted therein. The control consists of two like parts, each having one end secured together by an adjustable screw device 93. The parts may be manually separated by a wedge-like member 94 on a pivoted elbow lever 95, acted upon by the exterior push button 71, as shown in Figures 12 and 15. To avoid arcing, a shunt contact device 96 is secured to the switch rod 17 and this extends down to a high resistance stud 97 secured to the contact plate 98 in electrical contact with the exterior contact plate 12.

The plate 98 has recesses 101 engaged by tongues 102 of the control 98, and abuts against a shoulder 104. The plate 67 has diametrically arranged tongues or strips 67a formed into screw-threaded portions as seen in Figure 11, over which the screw-threaded socket 11 fits. When an excess of current passes through the control 90, it releases its hold on the enlarged part 91 of the switch rod 17, and permits it under the action of its spring 19 to ascend and leave the control. Electrical connection is still established through the rod 96 and stud 97. When the switch rod has ascended sufficiently so as to separate the end of the rod 96 and stud 97, then the final interruption of electrical contact takes place. The arrow 99 in Figure 13 shows the direction of movement of the rod 17. By this means, all injurious 45 arcing is avoided at the thermostatic control 90. Vents 100 are provided in the casing 10 to permit the flow of gas therethrough. The flow of current through the device shown in Figures 11 through 16 is from the shell 11 through wires 50 67a and plate 67 to the shaft 17, contact member 91, bi-metal element 91a, to the central terminal 12.

The various embodiments just described show the application of the different thermostatic control and contacts, in connection with the push button action described in detail in the first part of this specification, and not repeated in connection with Figure 11.

The embodiment shown in Figure 9, is also 60 embodied in the form shown in Figure 12.

The free tripping device then operates to insure against any repeated downward pressing of the push button, because the signal 84 will be visible to act as a warning. For instance, assuming an 65 overload, after the plug 91 has engaged the control 90, this overload will release the plug 91 from the control 90, and move the rod 17 upwardly regardless in which position the push button finds itself, which gives the signal 84 by the plug 16 acting on the plate 80. When the push button is then pressed downwardly, the sleeve 30 opens the jaws 26 and the rod 17 can pass freely through the fingers 27. Hence, no matter how many times the push button is pressed downwardly the rod is 70 75

always released. The same effect as just described in connection with an overload is naturally attained when the push button 71 is pressed down to mechanically unlock the control.

Having shown various embodiments of my invention and described the same, I do not wish to be limited to the particular embodiments described, as other forms may be proposed within the spirit of my invention as defined by the appended claims.

I claim:—

1. A circuit breaker having a casing, a movable rod therein for making or breaking the circuit, a spring plate for locking the rod in position, a 15 thermostatic plate for operating the spring plate in case of overload; a push-button for operating the rod, said button having means for pushing the rod in closed contact position and permitting release of said rod from said contact position 20 when the overload unlocks the rod while the button is pushed in.

2. A circuit breaker having a casing, a movable rod therein for making or breaking the circuit, a spring plate for locking the rod in position, a 25 thermostatic plate for operating the spring plate in case of overload; a push-button for operating the rod, said push-button having spring fingers with jaws therein for engaging said rod, means in the path of said spring fingers for opening said 30 jaws and permitting the rod to pass therethrough when unlocked by the spring plate.

3. A circuit breaker having a casing, a movable rod therein for making or breaking the circuit, a spring plate for locking the rod in position, a 35 thermostatic plate for operating the spring plate in case of overload; a plug on said rod to engage the locking spring plate, a spring disposed between said plug and a fixed part of the casing, a fixed sleeve supported by the casing having a 40 bore for the passage of the rod, a push-button having spring fingers with jaws, said jaws being adapted to engage the end of the rod passing through the spring fingers, said jaws being adapted to be opened to permit the passage there- 45 through of the rod, upon the jaws riding on said fixed sleeve upon the movement of the push-button in respect thereto, whereby upon the presence of an overload the rod is free to move between the jaws and to be forced by its spring out of 50 contact with the circuit.

4. A circuit breaker having a casing, a movable rod therein for making or breaking the circuit, a spring plate for locking the rod in position, a thermostatic plate for operating the spring 55 plate in case of overload; a push-button for operating the rod, said button having means for pushing the rod in closed contact position and permitting release of said rod from said contact position when the overload unlocks the rod, a 60 plate within the casing and an indicator on said plate normally within the casing, said plate being moved by the rod to force the indicator into an indicating position, when said rod is unlocked from the spring plate.

5. A circuit breaker having a casing, a movable rod for making or breaking the circuit, means to urge the rod into an open circuit position, a push-button for operating the rod, said button having means for pushing the rod into a 65 circuit-making position, means for moving said last named means into an inoperative position for permitting freedom of movement of said rod, and means rendered inoperative upon the existence of a predetermined excess current to hold 70 the rod in a circuit closing position.

6. Means for breaking an electric circuit comprising a casing, a movable member therein for making or breaking the circuit, means for urging the member into an open circuit position, means for holding the member in and releasing it from a closed circuit position, means for moving the member into circuit closing position, and means mounted on the casing within the path of the means for moving the member into circuit closing position for rendering the last-named means inoperative, said last-named means being independent of the structure of the means for breaking the circuit.

7. A circuit breaker having a casing, a movable member therein for making or breaking the circuit, means for urging the member into an open circuit position, means for holding the member in and releasing it from a closed circuit position, means for moving the member into circuit closing position, and means rendering the last-named means inoperative.

8. A circuit breaker having a casing, a movable member therein for making or breaking the circuit, means for urging the member into an open circuit position, means for holding the member in a closed circuit position, thermostatic means for releasing the holding means, means for moving the member into circuit closing position, and means operative during the final closing motion of the member to render the last-named means inoperative.

9. A circuit breaker having a casing, a movable member therein for making or breaking the circuit, means for urging the member into an open circuit position, means for holding the member in a closed circuit position, thermostatic means for releasing the holding means, yielding means for moving the member into circuit closing position, and means rendering the last-named means inoperative.

10. A circuit breaker having a casing, a movable member therein for making or breaking the circuit, means for urging the member into an open circuit position, means for holding the member in a closed circuit position, thermostatic means for releasing the holding means, an operating member, means movably mounted on the operating member for engaging the movable member to transmit motion from the operating member thereto, and means to disengage the last-named 50 member from the movable member.

11. A circuit breaker having a casing, a movable member therein for making or breaking the circuit, means for urging the member into an open circuit position, means for holding the member in a closed circuit position, thermostatic means for releasing the holding means, an operating member, means movably mounted on the operating member for engaging the movable member to transmit motion from the operating member thereto, and means operative during the final motion of the movable member into circuit closing position to disengage the last-named member from the movable member.

12. A circuit breaker having a casing, a movable member therein for making or breaking the circuit, means for urging the member into an open circuit position, means for holding the member in a closed circuit position, thermostatic means for releasing the holding means, an operating member, means movably mounted on the operating member for engaging the movable member to transmit motion from the operating member thereto, and a shouldered member on the casing to disengage the last-named member 75

from the movable member during final closing motion of the movable member.

13. A circuit breaker having a casing, a movable member therein for making or breaking the circuit, means for urging the member into an open circuit position, means for holding the member in a closed circuit position, thermostatic means for releasing the holding means, an operating member, means movably mounted on the operating member for engaging the movable member to transmit motion from the operating member thereto, a sleeve on the casing through which the movable member moves, and a shoulder on the sleeve in the path of the last named member to engage the same and disengage the said last named member from the movable member.

14. A circuit breaker having a casing, a movable member therein for making or breaking the circuit, means for urging the member into an open circuit position, means for holding the member in a closed circuit position, thermostatic means

for releasing the holding means, means for moving the member into circuit closing position, means rendering the last named means inoperative, an indicator, means to mount the indicator in the casing to be yieldingly urged into a non-indicating position, and means to move the indicator into an indicating position by the movable member. 5

15. A circuit breaker having a casing, a movable member therein for making or breaking the circuit, means for urging the member into an open circuit position, means for holding the member in a closed circuit position, thermostatic means for releasing the holding means, a spring pressed push button, yielding means on the button for engaging the member to move the member into circuit closing position, and means on the breaker to disengage the yielding means from the member during the final closing motion of the latter. 10 15

LAMBERT SCHMIDT. 20
